UNITED STATES PATENT OFFICE.

MARION B. RIFFO, OF PHILADELPHIA, PENNSYLVANIA.

PNEUMATIC CARRIER.

No. 853,987.

Specification of Letters Patent.

Patented May 14, 1907.

Original application filed December 18, 1905, Serial No. 292,396. Divided and this application filed October 13, 1906, Serial No. 338,730.

To all whom it may concern:

Be it known that I, MARION B. RIFFO, a citizen of the United States, residing in the city of Philadelphia, State of Pennsylvania, have invented certain new and useful Improvements in Pneumatic Service Carriers, of which the following is a full, clear, and exact description, reference being had to the accompanying drawings, forming a part of 5 this specification.

My invention relates to carriers for use in despatch tubes in pneumatically-operated service systems, and has for its object to provide means operating as well to limit the 15 relative rotation of its tubular members as also to maintain them in operative relation by preventing their accidental endwise dissociation in driving the carrier through the despatch tubes; the new means provided 20 therefor, and hereinafter described, has the additional advantage of permitting easy separation of the tubular members for repair or replacement of parts when worn out.

To attain these objects my invention consists of the combination with the tubular members of a carrier, of the novel elements hereinafter described, to perform the functions stated; my present application being a division of my pending and allowed application, Ser. No. 292,396, filed December 18, 30 1905.

In the drawings hereto annexed, in which the same letters of reference indicate like parts in the several views:—Figure 1 is a longitudinal sectional view of my improved carrier; and Fig. 2 is a transverse section on line 2—2 of Fig. 1; and Fig. 3 is a transverse section on line 3—3 of Fig. 1. Fig. 4 is a section showing a modification of the stop elements shown at right-hand end of Fig. 1.

In pneumatic service carriers as commonly constructed, the essential elements are a pair of cylindrical tubes, each having a closed head end and an open end, the tubes being 45 assembled sleeve-like, that is to say, telescoping, the open end of each tube brought to bear, directly or indirectly, against the head end of the other tube, both tubes being peripherally slotted longitudinally, the 50 slots being adapted to register on the relative rotation of the tubes, one within the other, and with means to limit the rotation, consisting of an outwardly projecting lug on the inner tube and a recessed extension of the 55 peripheral slot in the outer tube. These

devices are necessarily subjected to hard wear, tending to separate the tubes, by a springing of the outer tubular body, which wholly destroys their usefulness, and moreover the combination referred to prevents 60 easy repair of parts.

In my device hereinafter described, the tubular members are constructed as heretofore save for the modification of the open end of the inner tubular member, but the means 65 for operatively uniting them and limiting their relative rotation, are different, are new and of my invention, and these I will now describe.

The outer tubular member (Figs. 1 to 3) 70 is indicated at 2, and is a cylindrical tube having a head end 3 shown integral therewith, the opposite end being open. It is peripherally slotted, longitudinally, at 4. The inner tube 5 is similarly constructed, 6 75 indicating its closed head end, but its opposite open end has an inwardly projecting annular flange 25. These tubes are assembled by bringing the open end of the outer tube 2 over the open end of the inner tube 80 5, in sleeve-like manner, the tubes fitting each other reasonably close and adapted to rotate relatively, one within the other, so that the peripheral openings or slots 4 in the tubes may, by such relative rotation, be 85 brought into register or thrown out of coincidence.

Over the head end 6 of the inner tube 5 is fitted a cap or strengthening and closing plate 20, disk-like in form and having a projecting annular flange 21 alining with and abutting against the open end of the outer tube 2; this plate 20 being securely fastened to said head end 6 of the inner tube by a rivet 10, and both of them fastened, by removable 90 screw-bolts 9, to the buffer head 11 by means of inset blocks 22 and 23 therein.

Fitting tightly within the inner tubular member 5 at its flanged open end, is an annular plate 7 with an inwardly projecting annular flange 8. The central portion of this plate 7 is depressed to form an integral stop plate 19 (see Fig. 2) which abuts against the inner face of the head end of the outer tubular member 2. The depth of the depression in the plate 7, which forms the stop plate 19, is equal to the thickness of the inwardly projecting flange 25 on the inner tubular member, as seen at right hand of Fig. 1, consequently the peripheries of said stop 105 110

plate 19 and of said flange 25 are in the same vertical plane, and the former within the latter. The inwardly-facing peripheral edge of the flange 25 is a true circle, represented by 5 the heavy black line 26 and the dotted line-continuation thereof, see Fig. 2; but upon the arc between the termini of the dotted lines is a curved protuberance or thickness of metal, 29, operating as one engaging member 10 of a stop device. The co-acting disk-shaped stop-plate 19 is shown in Fig. 2 with a like character of peripheral protuberance, indicated at 28. The said disk 19 is a true circle indicated by the line 27 plus the dotted line 15 continuation thereof. The said elements are properly proportioned as to size, so as to form co-acting engaging surfaces. In said Fig. 2 the peripheral edges of the stop-plate 19 and inturned flange 25 of the inner tubular member 20 are shown in engaged position; and can be released therefrom only by a half turn to the left, of the inner disk 19, or a like turn to the right of the co-acting flanged member. Thus these members form in themselves, by relative rotation, a barrier or stop to limit such 25 rotation.

The tubes 2 and 5 are guided in relative rotation and they and the several parts are held from longitudinal displacement by the 30 flange 8 and the annular portion of the plate 7 which bears against the inturned flange 25 of the inner tube, because the stop plate 19 being a depressed portion of and integral with the plate 7 is securely fastened to the 35 head end of the outer tubular member 2 by the rivet 10 and both are fastened by removable screw bolts 9 to the adjacent buffer head 11 by means of the inset blocks 22 and 23. Thus the outer tubular member 2 with 40 its attached parts as stated is rotatable relatively to the inner tubular member; either inner or outer tube being actually rotated, depending solely upon which buffer head the turning force is manually applied. Such 45 rotative movement will move the co-acting engaging surfaces on the stop plate 19 and flange 25 of the inner tube, relatively to each other, and limit their relative rotation.

As will be observed from the foregoing description of the device, the new means 50 consists of the co-acting engaging surfaces on the coinciding peripheral faces of the inturned flange 25 of the inner tube 5 and on the stop plate 19 formed by the depressed portion of the flanged plate 7. I prefer to make said plate 7 with the flange 8 as described, only 55 because it assists in steadyng the tubes during rotation, and I prefer to make the stop plate 19 integral with said flanged plate 7 by depressing its central portion, hence said integral structure performs the treble function first, by its outer peripheral rim bearing against the inturned flange 25 of the inner tube 5, it holds the inner tube against longitudinal separation from the outer tube; sec-

ond, because of its integrality, the stop plate serves, through the screws 9 and 10, to hold the plate 7 against the flange 25 of the inner tube, for the purpose last stated; and third, by its depressed central portion, forming a 70 stop plate 19, it limits the relative rotation of the tubes 2 and 5.

It is obvious that the flange 8 on the plate 7 may be dispensed with, without altering the principle of construction and operation, 75 and equally obvious that instead of depressing the center of plate 7 to form the stop plate 19, it may be left intact in that regard to form a securing plate through which bolts 9 and 10 will pass, and the stop plate 19 then 80 be made a separate and distinct structure as illustrated in Fig. 4; however this is merely making the same device in two pieces instead of one, without changing its principle of construction and mode of operation. 85

The further operation of the device will be sufficiently well understood from the description already given; it being only desirable to call to attention that the elements and their combination and arrangement described will also operate to prevent normal longitudinal separation of the relatively rotatable telescoping tubes under ordinary conditions of use, while freely permitting their separation for repair or replacement of parts. 90

Having thus described my invention, I claim as new and desire to secure by Letters Patent:—

1. A carrier for pneumatic service systems comprising a pair of telescoping tubular members, peripherally slotted and arranged relatively rotatable, each provided with a closed head-end and an opposite open end, the inner of said tubular members having at its open end an inturned annular flange provided on an arc of its peripheral edge with a curved protuberance, a disk-like plate supported within said inturned flange and having a peripheral edge provided with a corresponding curved protuberance, said flange 100 and disk being adapted to be brought into or out of engagement on partial relative rotation, and with means to maintain said elements of the stop device in operative relation to each other and to the outer tubular member; substantially as described. 105

2. A carrier for pneumatic service systems consisting of a pair of cylindrical tubular members, arranged relatively rotatable and peripherally slotted, each provided with a 110 closed head end and an open end, the inner of said tubular members having at its open end an inturned annular flange provided with a curved engaging protuberance on an arc of its peripheral edge, a disk arranged to abut 115 against said inturned flange of the inner tubular member, and having its center depressed to form a stop plate the periphery of which is provided with a corresponding curved protuberance adapted to operatively 120

co-act with said flange of the inner tubular member and limit the rotation thereof relatively to the outer tubular member; with means to fixedly secure said stop plate of the 5 flanged disk to the head end of the outer tubular member; substantially as described.

In testimony whereof, I have hereunto af-

fixed my signature this 4th day of October A. D. 1906.

MARION B. RIFFO.
